DESIGN FOR A LENS PANEL FOR A LIGHTING FIXTURE

Edward C. Zimmerman, Winnetka, Ill., assignor
to Patent License Corporation, Chicago, Ill., a
corporation of Illinois

Application December 18, 1944, Serial No. 116,977

Term of patent 14 years

(Cl. D48—16)

To all whom it may concern:

Be it known that I, Edward C. Zimmerman, a citizen of the United States, residing at Winnetka, in the county of Cook and State of Illinois, have invented a new, original, and ornamental Design for a Lens Panel for Lighting Fixture, of which the following is a specification, reference being had to the accompanying drawing, forming a part thereof.

In the drawing:

Fig. 1 is a face view of the lens panel for lighting fixture showing my new design;

Figs. 2 and 3 are sectional views taken respectively on lines corresponding to lines 2—2 and 3—3 of Fig. 1;

Fig. 4 is an edge view of the panel; and
Fig. 5 is a bottom plan view of the panel.

The design is characterized by a light transmitting panel of the contour shown, in which a cavity is provided in the exposed surface of the panel, with a lens portion located on the wall of said cavity, said lens portion being transparent and protruding from the wall of the cavity, and the remainder of the panel being light diffusing, all as particularly illustrated in the drawing.

I claim:

The ornamental design for a lens panel for a lighting fixture, substantially as shown and described.

EDWARD C. ZIMMERMAN.
